BARBER'S COMB

Joseph K. Lambert, New York, N. Y.

Application December 2, 1939, Serial No. 307,197

5 Claims. (Cl. 132—11)

This invention relates generally to barber's combs and more particularly to combs that are used by barbers in the operation of trimming the hair.

5 In using a comb of this character the barber ordinarily takes it in his left hand, with the teeth pointing upwardly, lifts the hair tips by means of the toothed edge of the comb and, by means of scissors manipulated with the right hand, cuts off the ends of the hairs that project beyond the comb teeth. In order to regulate the length to which the hairs are cut, the barber manipulates the comb by a rolling or swivelling movement about its back, whereby the teeth of 10 the comb move away from the head, and as the comb teeth move away from the head the projecting ends obviously become shorter.

A second movement of the comb is a longitudinal one, however usually in a serpentine line, following the contours of the hair boundaries at the side of the head and the back of the neck or head, and this movement may be analyzed into components one of which is a translational movement in the plane of the comb, and the other is an angling movement in said plane about some point in the comb.

Among the objects of my invention is the provision in a barber's comb of a construction whereby the manipulation of the comb as hereinabove described is rendered more convenient and the operation of cutting the hair may be more conveniently and effectively carried out.

Among the more particular objects of my invention are further the provision in a comb of a concave back and the provision in a comb of convex areas between the teeth thereof disposed angularly in relation to the longitudinal extent of the teeth.

Among the objects of my invention is further the provision of a handle on a comb, whereby the manipulation of the comb is rendered more convenient because of the contours of the portions in contact with the hand and because of the more effective distribution of the weight.

Among the objects of my invention are also the provision in a barber's comb of a head-engaging surface that is provided with contours whereby the heretofore described rolling movement is facilitated and of peculiarly contoured comb teeth whereby the hair is more readily admitted between the teeth of the comb and is more effectively guided thereby.

The general object of my invention is the provision in a barber's comb of a simple, effective and economical construction.

These objects and such other objects as will hereinafter appear or be pointed out are attained in the illustrative embodiment of my invention shown in the drawing, in which:

Figure 1 is a front elevational view of my improved comb, portions being broken away to disclose the interior construction; 5

Figure 2 is a fragmentary view of a portion of the comb on an enlarged scale;

Figure 3 is a sectional view on the line 3—3 of 10 Figure 1 and 2;

Figure 4 is a view similar to Figure 3 showing a modification;

Figure 5 is a sectional view substantially on the line 5—5 of Figure 2; 15

Figure 6 is an end elevational view of the comb; and

Figure 7 is a view illustrating the manner of handling the comb.

Figure 1A is a view, more or less diagrammatic and similar to Figure 1, showing the curves of the outer edge of the back exaggerated, for purposes of illustration, this effect being obtained by reducing the length of the comb relatively to its width. 20

Referring now to the drawing in detail it will be observed that I have therein shown my improved comb as provided with a back portion 10 and a tooth portion comprising a set of relatively fine teeth 11 and a set of relatively coarse teeth 12. Seated on the back 10 of the comb at one end thereof is shown a handle portion 14. 25

The handle portion 14 is preferably of a thickness greater than that of the comb and of a weight that will tend to shift the center of gravity of the comb toward the handle end. The increased bulk of the handle end thus enables the operator to obtain a better grip on the comb, and manipulation of the comb during the rolling and 30 angling movements is greatly facilitated by the distribution of the weight so that it is more nearly concentrated in the handle end.

In the illustrative embodiment of Figure 1 the handle 14 is shown as of cylindrical form and as 45 hollow, whereby it has a contour that fits conveniently into the hand, as shown in Figure 7, and has adequate strength and adequate weight, without however having an excess of weight. The bore 14a of the handle 14 may extend completely therethrough or may be closed by an end wall 15 (see Fig. 6). It is also contemplated by my invention, if desired, to extend the back 10 of the comb into the bore 14a so as to form a web therein or to make the handle solid. These 50 55

alternative constructions have not been illustrated.

It will further be seen on referring to Figure 1 that the portions of the back 10 of the comb that are opposite the coarse teeth 12, are of substantial width, whereby in manipulating the comb, the thumb and fingers can obtain a good grip thereon, (see Figure 7), and this grip can be readily shifted lengthwise of the comb in effect 10 to either shorten or lengthen the comb in order more effectively to carry out desired manipulations.

The teeth 12 may be of conventional construction with both faces inclined as shown in Figure 15 6; the portion of the back 10 adjacent thereto from which the teeth 12 project may also be conventional except as to the handle portion to which further reference will be made. The tooth portion 11 however is different from the conventional construction, as clearly appears from the showing of Figures 2, 3, 4 and 5, and the portion 20 of the back 10 from which the teeth 12 project also differs from the conventional construction, as will be apparent from Figures 1, 2 and 3.

Upon viewing Figure 3 it will be observed that the teeth 11 are wedge shaped but that this wedge is formed in these teeth by one face which is parallel to the general median plane of the comb whereas the other face is inclined to this median 30 plane as contradistinguished from the teeth 12 shown in Figure 6 where the wedge shaped teeth have both surfaces inclined in reference to this median plane. The importance of this distinction will be pointed out hereinafter.

Beginning at a point such as A (see Figure 1) and extending toward the narrow end of the comb, which is the end opposed to the handle 14, the back 10 is concavely curved as shown at 19, whereby when the operator manipulates the 40 comb so as to roll the back edge on the head or on the hair, or to give it an angular movement in a longitudinal plane this concave back will conveniently follow the contours of the head and of the ear, enabling a more uniform hair cutting operation and greater accuracy on the part of the operator in estimating the length of the hair in the hair trimming operation, than is possible in combs having a straight back edge. The rolling operation is further facilitated by the curvature 50 of the side 18 of the comb that is held against the head during the hair cutting operation, as indicated at 17, it being understood that the rolling takes place about the back edge 10.

It will be observed that since the back edge of 55 the comb opposite the teeth 12 is convex, that the complete back may be described as being reversely curved.

Intermediate the teeth 11, that is, in the interstices between the teeth, the inner edge 21 of the frame 10 is cut away in a convexly curved surface 60 22, as clearly appears from Figures 2 and 3. This curved surface as viewed in section, may start at a right angle to the head engaging surface 18 of the comb as shown by the dot and dash line R in Figure 3, and may then extend toward the back of the comb.

I have found in practice that by so curving the surface portions between the teeth that the hair is lifted and bent upwards thereby enabling a 70 smooth hair cutting operation.

In the modified form of Figure 4, in which corresponding parts have been numbered similarly but the numerals have been primed, it will be observed that the curved surface 22' is shown as 75 starting at an angle that is acute, as indicated by

the dot and dash line R', and thereafter curving towards the back of the comb as it does in the form of Fig. 3.

An additional feature of my invention will be found fully illustrated in Figure 5, which shows 5 the teeth 11 in section. It will be observed that the teeth 11 may be described as generally of triangular conformation in section, with an apex 23 of the triangle at the head engaging surface 18 of the comb, and a side or base 24 of the triangle on the side of the comb away from the head. The interstices 25 between the teeth 11 are thereby contoured sectionally so as to have wide mouth or entrance portions 26 facing the head, into which hair can readily enter, while the narrow 15 portion 27 of the interstices guides the hair and holds it during the cutting operation.

The use of my improved comb will be understood from Figure 7 in which the operation of trimming the hair above the ear is illustrated. It 20 will be observed that the operator grasps the handle 14 with his hand H in the manner shown in the drawing and rests the concave back edge 19 of the comb on the ear of the subject. During this operation only the narrow forward end of 25 the comb with its fine teeth 11 is used. The great convenience of the concave edge 19 will at once be apparent from an inspection of Figure 7. It will be seen that the comb may be readily tilted about its support on the ear, the contacting portion 30 of the comb being located in its concave section 19. At the same time the aforesaid rolling motion is readily effected about the curved portion 17 of the comb which rests partly on the 35 ear and on the head.

When the operator works on the back of the head the concave edge 19 during the rolling manipulation will rest on and will merge with the contours at the back of the head more nearly than the straight edge, while at the same time it 40 does not interfere with a free longitudinal movement such as is necessary to pass from one portion of the head to another.

The formation of the wedge in the teeth 11 by one side which is inclined to the median plane of 45 the comb and a side which is not, is important in that it reduces the angle between the two faces by 50% so that the teeth 11 are brought into engagement with the hairs immediately adjacent to the line where the clipper stopped, with the inclined surface of the teeth 11 flat against the skin, and the angle which the other or upper surface makes with reference to the skin will be one-half of what it would be otherwise and therefore permit a much finer cutting operation than could otherwise be effected. In other words, I thereby attain a differential action upon the hair between the teeth 12 and 11 by the aforementioned difference between the two teeth.

While I have herein illustrated one embodiment of my invention and a modification thereof it will be understood that my invention may be embodied in many other forms as will be obvious to those skilled in the art without departing from the spirit thereof. It will further be understood that the disclosure herein is by way of illustration merely and is not to be interpreted in a limiting sense and that I do not limit myself other than as called for by the prior art.

Having thus described my invention and illustrated its use, what I claim as new and desire to secure by Letters Patent, is:

1. A barber's comb comprising a back and teeth projecting outwardly from said back, substantially one-half of the edge of said back ex- 75

tending between the middle and one end of said comb being concavely contoured so as to readily follow the contours of the head during angling or rolling movements of the comb incident to trimming the hair.

5. 2. A barber's comb comprising a back, teeth projecting from said back substantially along the entire length thereof, and a handle portion constituting one end of said back positioned at one 10 end of said comb, said handle portion being of substantially greater thickness than the other portions of said back which are substantially flat so as to afford an operator a better grip and to bring the center of gravity toward said handle 15 end.

3. A barber's comb comprising a back, teeth projecting from said back substantially along the entire length thereof, and a handle portion constituting one end of said back positioned at one 20 end of said comb, said handle portion being of substantially greater thickness than the other portions of said back which are substantially flat so as to afford an operator a better grip and to bring the center of gravity toward said handle 25 end, said handle portion being cylindrically contoured, and having a diameter of the order of the length of said teeth, projecting from said handle portion.

4. A barber's comb comprising a back, and 30 teeth projecting outwardly from said back, and a portion of the outer edge of the comb extending substantially from the midpoint of the comb to one end of said comb being concavely contoured, and the transverse cross-section of said comb 35 taken within the region where said outer edge is concavely curved being substantially quadrilateral with two long sides and two short sides, one of the latter lying in the outer edge of the back, and two opposed angles of the quadrilateral being 40 replaced by convex curves.

5. A barber's comb comprising a back and teeth projecting from said back throughout its length,

said teeth being divided into two groups, one having coarse teeth and the other fine teeth and one group arranged substantially between the midpoint of the comb in the direction of its length and one end of the comb, and the other group 5 arranged between said midpoint and the other end of the comb, said comb having the coarse teeth and the portion of the back from which they project disposed symmetrically about the longitudinal, medial plane of the comb, while the 10 fine teeth and the portion of the back from which they project is bounded on one side by a plane parallel to said medial plane and on the opposite side by a plane inclined to said medial plane, whereby said fine teeth are given a tapered 15 conformation, the portion of the back of said comb from which said coarse teeth project being relatively wide and the portion of the back of said comb from which the fine teeth project being relatively narrow, and the outer edge of the comb 20 being reversely curved whereby said relatively wide portion of the back is convexly curved and said relatively narrow portion of said back is concavely curved, and whereby said relatively wide portion gradually merges into said relatively narrow portion, the back of the comb being substantially flat except at and adjacent the outer end of said relatively wide portion, where it is expanded laterally to thicken it substantially into a handle portion, and the traverse cross-section 30 of the back of the comb between adjacent fine teeth being a modified trapezoid with one side parallel to the medial plane and the opposite side inclined to the medial plane, and the corner that would normally be formed at the meeting of the 35 back edge of the comb and the inclined side being replaced by a convex curve, and the corner that would normally be formed by the said parallel side and the inner edge of the comb between the teeth, being also replaced by a convex curve. 40

JOSEPH K. LAMBERT.
